UNITED STATES PATENT OFFICE.

JOHN G. LEPPER, OF WATERBURY, CONNECTICUT, AND ALVIN MATTIS, OF ROYERSFORD, PENNSYLVANIA, ASSIGNEES TO BOOTH, SCHELLINGER AND WILLIAMS COMPANY, A CORPORATION OF DELAWARE.

BOTTLE-MAKING MACHINE.

1,168,517.

Specification of Letters Patent.

Patented Jan. 18, 1916.

Application filed October 28, 1912. Serial No. 728,282.

To all whom it may concern:

Be it known that we, JOHN G. LEPPER, a citizen of the United States, residing at Waterbury, in the county of New Haven 5 and State of Connecticut, and ALVIN MATTIS, a citizen of the United States, residing at Royersford, in the county of Montgomery and State of Pennsylvania, have invented a new and useful Improvement in Bottle- 10 Making Machines, of which the following is a specification.

This invention relates generally to bottle making machines, and more particularly to certain improvements upon the bottle making machine shown and described in the application filed October 18, 1911, Serial Number 654,481.

In the machine referred to the bottle finishing tool is carried upon the end of a rotatable spindle, which is forced downwardly and upwardly by means of an arm positively operated, said downward and upward movements taking place at predetermined times and brought about by actuating 25 mechanisms connected with the machine.

In our present invention which pertains more particularly to the finishing tool and actuation thereof, the rotatable spindle is balanced or suspended in mid air and the 30 lowering thereof is incidental to the actuation of the tool. Furthermore in the present improvement the actuating mechanism is preferably gravity operated and positively returned but nevertheless there is an 35 independent movement between the said gravity actuated mechanism and the positive return mechanism.

In the present improvement we also provide a positive locking means for holding 40 the spinning tool and actuating mechanism in their normal elevated positions, said locking device being tripped or released by means of a stop which can be arranged at a predetermined point so as to release the 45 mechanism and permit the finishing tool to be lowered and actuated at the exact point for engaging the bottle neck.

The object of all of these features of construction and operation is to provide for the 50 accurate and uniform finishing of the bottle neck and compensating for any shortage or surplusage of material in the re-heated neck of the bottle.

With these various objects in view, our

invention consists in the novel features of 55 construction, combination and arrangement of parts all of which will be fully described hereinafter and pointed out in the claims.

In the drawings forming a part of this specification: Figure 1 is a side view of a 60 portion of the bottle finishing machine showing the practical application of our invention. Fig. 2 is an enlarged view taken from the opposite side and showing the locking and releasing mechanisms. 65

Referring to the drawings A indicates the base of the machine and B the upright standard connected thereto, and C the bottle mold which is arranged upon a base C' fixed upon a rotatable turret. (Not shown.) 70

D indicates the spindle carrying the bottle finishing tool E at its lower end, the details of this tool being more fully described hereinafter. The spindle D has stop collars D' and D'', which respectively limit its 75 downward and upward movements, it being understood that the spindle passes through bearings rigidly attached to the standard B and this spindle D is rotated back and forth by means of the spindle 80 rotating mechanism F arranged upon the top of the standard B and forming the subject matter of an application filed January 12, 1912, Serial Number 670,887. This spindle D is suspended or balanced by means of a 85 cable G passing over pulleys G' carried by a bracket G'' bolted to the standard B, said cable having a weight or weights G''' attached to the end thereof, said weight being just sufficient to maintain the spindle and 90 attached tool in a balanced or floating condition.

It will be understood that any suitable swivel connection may be employed to connect the cable to the top of the spindle so 95 as to permit said spindle to be rotated during its up and down movements.

The finishing tool E comprises the plug E' at the lower end and the arms E'' carrying the jaws E''' which coöperate with the plug E' 100 to produce the desired shape of bottle neck. The arms E'' are pivoted at E'' to a casting E'' attached to the spindle and at their upper ends are united by means of a spring E''. Each arm E'' carries a supplemental arm E''' 105 which is provided with frictional rollers E''' at its upper end and an adjusting screw E''' at its lower end. These supplemental arms

E⁷ are adapted to be engaged by a sliding collar H movable upon the spindle, the lower end thereof being tapered, conical or wedge-shaped as shown at H' so that as the collar H is forced down upon the spindle the tapered end passing between the arms E⁷ will readily expand them carrying with them the arms E² and bringing the jaws E³ inwardly upon the neck of the bottle, the plug E' having entered the neck of the bottle as the jaws E³ are being forced inwardly. Any further movement of the collar H after passing the inclined portion H' will have no effect upon the jaws so far as their separation is concerned for the reason that the upper portion of the collar H is of uniform diameter. The frictional engagement of the tapered or inclined portion of the collar H with the arms E⁷ is sufficient to cause the spinning tool and spindle to be lowered inasmuch as they are suspended in a balanced condition and consequently the slight downward pressure applied thereon during the expanding operation is sufficient to carry these elements downwardly.

For the purpose of moving the collar H downwardly we employ an arm I which is mounted upon the end of a short shaft I' journaled in a bearing formed in the standard B and a second arm K is also rigidly attached to this short shaft I' and moves in unison with the arm I, and attached to said arm K is a weight K' which is slightly greater than the weight G³ so that when the arm I is released the weight K will be sufficient to carry the arms K and I downwardly overcoming the counter-balance G³ and causing the spindle and tool to move downwardly, the free end of the arm I being bifurcated and engaging the grooved upper end of the collar H.

For the purpose of holding the arm I in an inoperative position we employ a locking lever L pivoted at L' to the standard B, the upper end of said lever being held against a stop pin L² by means of a spring L³ connected to the standard and when in this position the upper end of the stop lever L engages a plate or block M clamped or otherwise secured to the arm I and it is obvious that so long as the upper end of the lever L rests beneath this block M the arm I cannot descend.

For the purpose of tripping or releasing the locking lever I, we employ a striker lug or pin N, which is fixed to the mold base at such a point that as the mold moves around beneath the finishing tool this striker pin or lug N will engage the lower end of the lever L throwing the upper end out of engagement with the block M and the weight K' immediately acts to set the arms K and I descending carrying with them finishing tool and spindle, these parts being shown in this position in Fig. 2 of the drawing. As the

finishing tool descends the jaws thereof engage the re-heated neck of the bottle and being rotated first in one direction and then in the other the neck of the bottle is properly and accurately shaped. The arm K and consequently the arm I are returned to their normal position or upper positions by means of a pitman P operated by the cam wheel P' and it will be noted that the upper end of this pitman P is formed with an open crotch 75 P² in which rests the pin K² carried at the end of the arm K and a coil spring K³ serves to keep these parts in engagement. By means of this construction it is obvious that the pitman P can have a downward movement independent of the movement of the arm K, for if the striker pin or lug N should for any reason fail to engage the lower end of the locking lever L, said lever will remain in engagement with the arm I and hold the 85 same elevated thereby preventing the finishing tool descending into the bottle neck but the pitman operated from the power shaft can continue its movements without disturbing the finishing tool. By means of this 90 construction and arrangement we are enabled to hold the finishing tool inoperative except when the bottle has been properly positioned therebeneath, for the reason that the striker pin can be accurately adjusted so 95 as to actuate the lever L just at the proper time to cause the spinning tool to descend exactly in the center of the bottle neck, and hold the same inoperative at all other times. By means of the set screws E⁹ relative movement of the arms E² can be regulated.

When the arm K is lifted by the pitman P, the spindle and finishing tool will be carried up at the same time thereby lifting the finishing tool clear of the finished bottle 105 neck, and the first portion of the upper movement of the arm I will of course be to release and separate the jaws E³ and the continued upward movement will completely remove the finishing tool from the neck of 110 the bottle ready for the next operation. It will also be understood that the moment the arm I is lifted a sufficient distance the spring L³ will draw the locking lever back so as to throw its upper end into engagement with 115 the block N clamped to the side of the arm I.

It will of course be understood that the details of our structure may be changed or varied to suit various circumstances without departing from the broad principle of our 120 invention.

What we claim is:—

1. A device of the kind described comprising a counterbalanced spindle carrying a finishing tool at its lower end, gravity 125 operated means for lowering said spindle and tool together with gravity operated means for raising said spindle to its normal position.

2. A device of the kind described com- 130

prising a balanced spindle, a finishing tool arranged at the lower end of said spindle, said spindle being vertically movable and rotatable, means for actuating the elements of said finishing tool, said actuation of the finishing tool serving to overcome the balance of said spindle and cause the same to descend simultaneously with the operation of the finishing tool.

10 3. A device of the kind described comprising a spindle, a finishing tool carried at the lower end of said spindle, means attached to the opposite end of said spindle for maintaining said spindle in a suspended position, means operating upon said finishing tool for actuating the same and simultaneously lowering said spindle, and means for returning the tool actuated mechanism to its normal position and whereby the 20 spindle suspending means can become operative again to elevate and suspend said spindle.

4. In a device of the kind described a balanced suspended spindle carrying a finishing tool at the lower end thereof, said spindle being rotatable and also vertically movable, an arm for actuating said tool and causing the spindle to descend, a locking lever for holding said arm inoperative together with means for disengaging said locking lever, thereby permitting the actuating arm to become operative for the purpose set forth.

5. In a device of the kind described a balanced and suspended rotatable spindle carrying a finishing tool at the lower end thereof, a gravity operated arm adapted to actuate said tool and cause the spindle to descend, a lock-

ing lever for holding said arm inoperative, means for disengaging said lever, and positive means for returning the tool actuating arm to its normal position and permit the suspending means of the spindle to elevate the same.

6. In a device of the kind described a balanced spindle carrying a finishing tool at the lower end thereof, an arm and collar for actuating said tool and simultaneously causing the spindle to be lowered, said spindle being normally suspended in a balanced state, a locking lever for holding said arm inoperative, together with means for disengaging said lever and a pitman for raising said actuating arm.

7. In a device of the kind described, a 55 rotatable spindle carrying a finishing tool at its lower end, said spindle being movable vertically and normally suspended by a counterbalance, a gravity actuated arm adapted to operate the finishing tool and simultaneously cause the spindle to descend, a locking lever adapted to hold said arm inoperative, means for disengaging said locking lever, together with means for returning said actuating arm to its normal position and thereby permit the counterbalance of the spindle to restore the said spindle to its normal balance position.
